UNITED STATES PATENT OFFICE.

ARTHUR J. BRIGGS, OF SYRACUSE, NEW YORK, ASSIGNOR TO REMINGTON TYPE-WRITER COMPANY, OF ILION, NEW YORK, A CORPORATION OF NEW YORK.

TYPEWRITING-MACHINE.

1,368,017.

Specification of Letters Patent. Patented Feb. 8, 1921.

Application filed April 26, 1919. Serial No. 293,007.

To all whom it may concern:

Be it known that I, ARTHUR J. BRIGGS, citizen of the United States, and resident of Syracuse, in the county of Onondaga and State of New York, have invented certain new and useful Improvements in Typewriting-Machines, of which the following is a specification.

My invention relates to typewriting machines and more particularly to platen clutches.

One object of my invention is to provide a strong, highly efficient and comparatively simple platen clutch mechanism, the parts of which can be readily assembled, and which can be manufactured at comparatively small cost.

A further object of my invention is to provide a platen clutch which in the main is arranged outside of the platen proper so that a substantially solid platen core may be employed to reduce the noise which ordinarily occurs from the impact of types against a platen provided with a hollow core.

A still further object of my invention is to provide a platen clutch of the character described which can be readily embodied in existing machines, such for example as the Nos. 10 and 11 Remington machines without modifying the structural features of such machines to receive platens equipped with clutch mechanism of my invention.

To the above and other ends which will hereinafter appear my invention consists in the features of construction, arrangements of parts and combinations of devices set forth in the following description and particularly pointed out in the following claims.

In the drawings wherein like reference characters represent corresponding parts in the various views,

Figure 1 is an enlarged detail end view of the platen with the cover plate removed to expose the clutch, the parts appearing as viewed from the direction of the arrow in Fig. 2.

Fig. 2 is an enlarged detail fragmentary longitudinal sectional view of the right-hand end portion of the platen, the section being taken on the line $x-x$ of Fig. 1 and

looking in the direction of the arrow at said line. 55

Fig. 3 is a like view of the same taken at right-angles to the section illustrated in Fig. 2, or on the line $y-y$ of Fig. 1 and looking in the direction of the arrow at said line. In Fig. 3 the platen is shown supported at its right-hand end in the platen frame, the usual platen clutch catch appearing in this view.

Fig. 4 is an enlarged detail fragmentary inside view of the clutch as seen when viewed from a direction opposite to that indicated by the arrow in Fig. 2.

Fig. 5 is a view corresponding to Fig. 2 but showing the parts as they appear when the clutch is released.

Fig. 6 shows separated and in perspective different parts of the clutch in order more clearly to illustrate the details thereof.

While in the present instance I have shown the bearing for the platen only at 75 the right-hand end thereof in Fig. 3, it will be understood that the platen may be mounted in the platen frame of a No. 10 or No. 11 Remington machine in the usual manner. 80

It also will be understood that the line spacing pawl 1 and spring detent roller 2 may coact with the line spacing wheel in the ordinary manner.

The platen designated as a whole by the reference numeral 3 comprises a sheath 4 and a core 5 which latter preferably is solid substantially throughout the length thereof. One end of the platen has a platen head, designated as a whole by the reference numeral 6, secured thereto by screws 7. A circular flange 8 projects from the inner face of the platen head and is received and seated in a corresponding opening 9 in the core 5 of the platen, in order 95 to properly center the platen head and form an additional support therefor on the platen. The platen head has a central rectangular opening 10 extending therethrough, opposite parallel side walls 11 of which 100 are formed in part by inner faces of two outwardly projecting lugs 12 and 13 on the platen head. These lugs terminate short of the periphery of the platen head and extensions 14 project outwardly from 105 the lugs 12 and 13 near the walls 11 there-

of, for purposes which will hereinafter appear. A line spacing wheel 15, in the nature of a ring, has formed on the inside thereof a circular cut-out or bearing groove 16 by which the wheel is adapted to receive and be seated on the periphery of the platen head, and is thus mounted to turn thereon. When the line spacing wheel is in place it surrounds the lugs 12 and 13, as shown in Fig. 1, and a clutch member or section in the form of a split ring 17 is contained within the line spacing wheel and is adapted to coact with the inner cylindrical surface 18 of the latter. Each end of the split ring 17 is preferably enlarged to provide a contact face 19 of greater radial dimensions than the thickness of the body portion of the ring. Interposed between each end 19 of the ring 17 and the lug 12 on the platen head is a controlling member designated as a whole by the reference numeral 20. Each member 20 is preferably formed of sheet metal and is in the nature of a lever that extends transversely of the axis of the platen 25 and is substantially L-shaped in form, one arm 21 of each lever being offset and slightly twisted or skewed relatively to its other arm 22 in order to provide an inclined face or cam 23 at the inner side 30 of each of the arms 22. When these levers are assembled in place the outer end of each arm 22 is seated between one side of the lug 12 and the adjacent end 19 of the split ring, the faces of the arms 22 of the two levers being parallel, or substantially so, when bearing flat against the lug 12. The arms 21 of the levers, however, extend longitudinally of the platen through the rectangular opening 10 in the platen head 40 with the inclined faces 23 thereof in planes which converge toward the axis of the platen as the outer edges of the faces are approached.

It will be understood that when the inner ends of the levers 20 are separated, or moved to the positions shown in Fig. 4, by means to be hereinafter described, one end of each lever will fulcrum against the lug 12 and will spread the ends of the split ring apart, thus effectively forcing the ring against the inner face 18 of the line spacing wheel, and by the clutching action thus established cause the line spacing wheel and platen to turn together. The split ring is preferably made 55 of cast iron and is sufficiently resilient to contract when relieved from the force exerted by the levers 20, and this contraction of the ring releases it from clutching engagement with the line spacing ring and forces 60 the levers back to positions where the portions 22 thereof are parallel and rest with their inner flat faces against the lug 12.

It will be seen that the inner edges 24 of the levers 20 bear against the outer face of 65 the platen head 6 and are confined in place

by a cover plate, designated as a whole by the reference numeral 25. This cover plate is secured by headed screws 26 to the platen head, the screws passing freely through openings 27 in the cover plate and engaging in tapped openings 28 in the lugs 12 and 13. A central circular depression 29 formed in the inner face of the cover plate receives the lugs or extensions 14 on the platen head, said extensions snugly fitting the depression in order to center the plate 25 on the platen head and form an additional support for the plate. The cover plate not only constitutes one side wall of a housing and confines the levers in place therein, but also confines the split ring within the housing and overlaps the line spacing wheel and holds it in place on its bearing on the platen head. The cover plate is formed with a central opening 30 which extends therethrough and through an outwardly projecting hub 31 formed on the plate. From an inspection of Fig. 3 it will be understood that this hub 31 is received in the usual bearing, bushing or sleeve 32 threaded into a tapped opening in the platen frame 33 and held in its adjusted position by a lock nut 34. The right-hand end of the platen is thus supported in place on the platen frame.

The means for controlling the levers 20 to effect an engagement or disengagement of the clutch will now be described.

A spindle 35 is disposed axially of the platen and is seated in and passes freely through the central opening 30 in the cover plate and its hub and through the bushing 32. This spindle is provided at its outer end with a finger wheel 36 and terminates at its inner end near the right-hand end of the platen within the line spacing wheel. The inner end portion of the spindle is provided with a portion or head 37 which is rectangular in cross section. This is in order to provide on opposite sides of the head parallel flat faces 38 which fit between the flat faces 110 or walls 11 on the platen head and coact therewith to cause the spindle and platen to turn together, the spindle being enabled, however, to receive an independent movement longitudinally of the platen. The head 115 37 has a cylindrical bore, recess or opening 39 extending entirely therethrough transversely of the axis of the spindle. This bore constitutes a ball chamber, containing preferably two anti-friction rollers or balls 120 which fit the bore and bear one against another and are free to move transversely of the axis of the spindle but are constrained to move bodily with the spindle in the axial movements of the latter. From an inspection 125 of Figs. 2 and 5 it will be seen that the head 37 is received between the levers 20, and that the anti-friction balls 40 extend beyond the ends of the bore 39 and beyond the sides of the spindle or its head. The balls 130

are thus enabled to contact with the oppositely inclined faces 23 of the levers, having a rolling contact with the latter as the spindle moves longitudinally. The inner 5 end of the spindle is formed with a circular lug 41 which is received in the outer end of a coiled expansion spring 42. This spring is contained within an opening or recess 43 in the core of the platen and bears at its inner 10 end against the bottom wall 44 of said recess. A metal sleeve 45 may be seated tightly in the recess 43 and surrounds the spring 42. One end of the sleeve may be provided with a circular flange 46 that seats 15 against the core and limits the inward movement of the sleeve. From a consideration of Fig. 1 it will be understood that the corner portions of the square head 37 of the spindle are adapted to abut the flange 46 20 when the spindle is pushed in, thus limiting its inward or releasing movement, and limiting the movements of the parts controlled thereby.

The force of the expansion spring is exerted to normally maintain the parts in the 25 positions shown in Figs. 1, 2 and 4, thus forcing the balls along the oppositely inclined faces of the levers and separating the inner ends thereof to expand the split ring 30 and maintain the line spacing wheel clutched to turn with the platen. When, however, the spindle 35 is moved longitudinally by the finger wheel 36, from the position shown in Fig. 2 to that indicated in Fig. 5, the balls 35 will roll along the inclined faces of the levers, relieving the wedging action on the latter and permitting the inner ends of the levers to approach one another under the contraction of the split ring, thus releasing 40 the clutch and enabling the platen to be turned by the finger wheel. At this time the platen will turn independently of the line spacing wheel since the clutch is released and the line spacing wheel is held 45 against movement with the platen by the spring roller detent 2. When the spindle is moved to its releasing position, as pointed out above, a catch 47, such as is employed in the Remington machine, may be caused to 50 engage the usual circumferential flange 48 on the hub of the finger wheel 36, thus locking the spindle in its releasing position while the necessary rotative adjustment of the platen by the finger wheel is being effected. A release of the catch enables the parts 55 to return to their normal positions and connect the line spacing wheel to turn with the platen.

By reason of the fact that pressure exerted 60 to expand the split ring is transmitted through the anti-friction balls which bear one against another, and which are free to move transversely of the axis of the spindle, such pressure will be effectively applied at 65 both ends of the split ring, the pressure at

one end being balanced against pressure applied at the other end and rendered self-compensating. There is no opportunity for the parts to become cramped, or an ineffective action of the clutch to take place, and 70 there is no necessity for the provision of adjusting means, or for securing a nice adjustment of the parts in order to assure an effective operation of the clutch.

Moreover, the application of the power 75 of the spring through the rolling anti-friction balls, in the manner described, enables a lighter spring to be employed with a greater degree of effectiveness than could ordinarily be used. 80

It will be observed from the foregoing that the split or divided ring is arranged within the line spacing wheel; that the platen head is provided with a lug or fulcrum block which is arranged between the 85 terminals of said ring; that the loose plate-like levers are arranged within the ring and crosswise thereof, each lever at its outer end being arranged between one end or terminal of the ring and one side of the fulcrum 90 block; that the inner ends of said levers extend toward the middle of the ring but each to one side of the center thereof at which locality each lever is provided with a flaring portion or cam that extends longitudinally 95 of the axis of the ring and also of the platen; that the stem 35 is arranged axially of the platen and of the ring and is provided at its inner end within the ring with a head that is formed with a transverse bore which contains two balls always in contact within the bore and each of which protrudes beyond the bore and is arranged to bear and roll along the cam portion of its associate lever when the stem is moved longitudinally; and that 100 the spring which acts upon said head normally presses the stem outwardly and causes the balls to press upon the levers, said levers under this pressure fulcruming on the fulcrum block and bearing upon the terminals 105 of the split ring as levers of the second order to cause the expansion of the ring against the interior surface of the surrounding line space wheel. 110

It will be understood that the parts may 115 be quickly assembled by merely placing them together in the manner shown and securing the cover plate in place; that no test or adjustment is required to determine the effectiveness of the clutch; that the clutch is 120 simple, strong and efficient in use; that the parts are not apt to become disarranged or broken; that the construction enables a platen core solid substantially throughout the length thereof to be employed; and that 125 the construction may be manufactured and assembled at small cost and applied to existing machines without changing such machines to receive platens equipped with clutch mechanism of my invention. 130

Changes may be made without departing from my invention and certain features thereof may be employed without others.

What I claim as new and desire to secure by Letters Patent, is:—

1. The combination of a rotative platen; a line spacing wheel; and clutch mechanism for connecting the line spacing wheel and platen to turn together or for disconnecting them so that the platen may be turned independently of the line spacing wheel, said clutch mechanism comprising a hand controlled member operable at will and having a ball containing chamber or pocket there-in, two contacting balls contained in said chamber or pocket and free to move therein together in a direction transverse to the direction of movement of said member, and clutching means including elements along which said balls are adapted to roll and which are actuated thereby, and a split ring which coacts with the line spacing wheel and is controlled by said elements.

2. The combination of a rotative platen; a line spacing wheel; and clutch mechanism for connecting the line spacing wheel and platen to turn together or for disconnecting them so that the platen may be turned independently of the line spacing wheel, said clutch mechanism comprising a hand controlled member fixed to turn with the platen and by which the platen may be turned but which is independently movable longitudinally of the platen, said member having a ball containing chamber or pocket therein, two contacting balls contained in said chamber or pocket and free to move therein together in a direction transverse to the direction of the independent movement of said member, and clutching means including a pair of levers disposed on opposite sides of said balls and fulcrumed to move in a plane which extends transversely of the axis of the platen, each of said levers having an inclined face along which a ball is adapted to roll and thus control the movement of the levers and the opening and closing of the clutch.

3. The combination of a rotative platen; a line spacing wheel; and clutch mechanism for connecting the line spacing wheel and platen to turn together or for disconnecting them so that the platen may be turned independently of the line spacing wheel, said clutch mechanism comprising a spindle which terminates near one end of the platen and which is provided at its outer end with a finger wheel by which the platen may be turned, means for connecting said spindle to turn with the platen but affording a movement thereof longitudinally and independently of the platen in order to control the release and engagement of the clutch, a ball receiving chamber or pocket formed in said spindle, one or more balls contained in

said pocket and movable with the spindle in the longitudinal movement of the latter, a spring which tends to move said spindle longitudinally in one direction, clutch controlling levers on opposite sides of said ball or balls and controlled by the latter, and a split ring which is adapted to be expanded against the line spacing wheel and clamp the wheel so that it will turn with the platen, the levers coacting with said split ring to control the expansion and contraction thereof.

4. The combination of a rotative platen; a line spacing wheel; and clutch mechanism for connecting the line spacing wheel and platen to turn together or for disconnecting them so that the platen may be turned independently of the line spacing wheel, said clutch mechanism comprising a platen head secured to the platen and on which the line spacing wheel is adapted to turn, a split ring contained within the line spacing wheel and adapted to bear against it and connect the wheel to turn with the platen, a pair of levers loosely disposed and fulcrumed on the platen head and coacting with the split ring to control the expansion and contraction thereof, each of said levers having an inclined face, a spindle disposed axially of the platen and operatively connected to turn the platen but adapted to move longitudinally independently thereof, a finger wheel at the outer end of said spindle, and a pair of anti-friction balls carried by said spindle between said levers, and operative on the inclined faces thereof to control the levers in their operating movements.

5. The combination of a rotative platen; a line spacing wheel; and clutch mechanism for connecting the line spacing wheel and platen to turn together or for disconnecting them so that the platen may be turned independently of the line spacing wheel, said clutch mechanism comprising a platen head secured to the platen and on which the line spacing wheel is adapted to turn, a split ring contained within the line spacing wheel and adapted to bear against it and connect the wheel to turn with the platen, a pair of levers loosely disposed and fulcrumed on the platen head and coacting with the split ring to control the expansion and contraction thereof, each of said levers having an inclined face, a spindle disposed axially of the platen and operatively connected to turn the platen but adapted to move longitudinally independently thereof, said spindle having a bore that extends transversely therethrough, and a pair of anti-friction balls loosely contained in said bore and extending beyond the sides of the spindle where the bore is formed and into contact with the inclined faces on said levers.

6. The combination of a rotative platen; a line spacing wheel; and clutch mechanism

for connecting the line spacing wheel and platen to turn together or for disconnecting them so that the platen may be turned independently of the line spacing wheel, said 5 clutch mechanism comprising a platen head secured to the platen and having a central opening therethrough that is formed with parallel flat side walls, an axially disposed spindle formed with a section having side 10 walls that conform to and coact with said flat side walls of the opening through the platen head, whereby the spindle and platen head are connected to turn together but the spindle may receive a longitudinal movement 15 independently of the platen head, a bore extending transversely entirely through said spindle, anti-friction rollers loosely contained in said bore and bearing one against another and extending beyond the 20 ends of the bore, and clutch controlling means with which said rollers coact.

7. The combination of a rotative platen; a line spacing wheel; and clutch mechanism for connecting the line spacing wheel and 25 platen to turn together or for disconnecting them so that the platen may be turned independently of the line spacing wheel, said clutch mechanism comprising a platen head secured to the platen and having a central 30 opening therethrough that is formed with parallel flat side walls, an axially disposed spindle formed with a section having side walls that conform to and coact with said flat side walls of the opening through the 35 platen head, whereby the spindle and platen head are connected to turn together but the spindle may receive a longitudinal movement independently of the platen head, a bore extending transversely entirely through 40 said spindle, anti-friction rollers loosely contained in said bore and bearing one against another and extending beyond the ends of the bore, clutch controlling means with which said rollers coact, a finger wheel 45 at one end of said spindle and by which the platen may be turned, and a spring co-acting with the spindle at the other end thereof and tending to move the spindle longitudinally in one direction.

50 8. The combination of a rotative platen; a line spacing wheel; and clutch mechanism for connecting the line spacing wheel and platen to turn together or for disconnecting them so that the platen may be turned independently of the line spacing wheel, said 55 clutch mechanism comprising a platen head secured to the platen and having a central opening therethrough that is formed with parallel flat side walls, an axially disposed 60 spindle formed with a section having side walls that conform to and coact with said flat side walls of the opening through the platen head, whereby the spindle and platen head are connected to turn together but the 65 spindle may receive a longitudinal move-

ment independently of the platen head, a bore extending transversely entirely through said spindle, anti-friction rollers loosely contained in said bore and bearing one against another and extending beyond the 70 ends of the bore, a finger wheel at one end of said spindle and by which the platen may be turned, a spring co-acting with the spindle at the other end thereof and tending to move the spindle longitudinally in one direction, a pair of levers fulcrumed on the platen head and disposed on opposite sides of said rollers and having inclined faces against which the rollers are adapted to bear and along which they are adapted to 75 roll, and clutching means controlled by said levers.

9. The combination of a rotative platen; a line spacing wheel; and clutch mechanism for connecting the line spacing wheel and 80 platen to turn together or for disconnecting them so that the platen may be turned independently of the line spacing wheel, said clutch mechanism comprising a platen head secured to the platen and having a central 85 opening therethrough that is formed with parallel flat side walls, an axially disposed spindle formed with a section having side walls that conform to and coact with said flat side walls of the opening through the 90 platen head, whereby the spindle and platen head are connected to turn together but the spindle may receive a longitudinal movement independently of the platen head, a bore extending transversely entirely through 95 said spindle, anti-friction rollers loosely contained in said bore and bearing one against another and extending beyond the ends of the bore, a finger wheel at one end of said 100 spindle and by which the platen may be turned, a spring co-acting with the spindle at the other end thereof and tending to move the spindle longitudinally in one direction, a pair of levers fulcrumed on the platen head and disposed on opposite sides 105 of said rollers and having inclined faces against which the rollers are adapted to bear and along which they are adapted to roll, and a split ring adapted to coact with the line spacing wheel and with the ends of 110 which said levers coact to control the expansion and contraction of the ring.

10. The combination of a rotative platen; a line spacing wheel; and clutch mechanism for connecting the line spacing wheel and 115 platen to turn together or for disconnecting them so that the platen may be turned independently of the line spacing wheel, said clutch mechanism comprising a controlling lever formed of sheet metal and having an 120 inclined operating cam face formed by skewing or twisting one section of the lever to a different angular plane from the body portion thereof.

11. The combination of a rotative platen; 125

a line spacing wheel; and clutch mechanism for connecting the line spacing wheel and platen to turn together or for disconnecting them so that the platen may be turned independently of the line spacing wheel, said clutch mechanism comprising a substantially L-shaped controlling lever one arm of which is skewed or twisted to a different angular plane relatively to the other arm in order to form an inclined operating face or cam.

12. The combination of a rotative platen; a line spacing wheel; and clutch mechanism for connecting the line spacing wheel and platen to turn together or for disconnecting them so that the platen may be turned independently of the line spacing wheel, said clutch mechanism comprising a substantially L-shaped controlling lever fulcrumed 70 at the free end of one of its arms and having the other arm skewed or twisted to a different angular plane in order to form an inclined operating face or cam.

13. The combination of a rotative platen; a line spacing wheel; and clutch mechanism for connecting the line spacing wheel and platen to turn together or for disconnecting them so that the platen may be turned independently of the line spacing wheel, said clutch mechanism comprising a platen head secured to the platen and having a central opening extending therethrough, and a substantially L-shaped sheet metal controlling lever having the free end of one of its arms fulcrumed against the platen head so that the movement of the lever is in a plane which extends transversely of the platen, the other arm of the lever being skewed or twisted relatively to said first mentioned arm to form an inclined or cam face and extending through said opening in the platen head and longitudinally of the platen.

14. The combination of a platen, a platen head secured directly to the platen, a line spacing wheel mounted directly on the platen head to turn thereon, clutch devices mounted on the platen head and operative to clutch the line spacing wheel to cause it and the platen to turn together, a controlling spindle for controlling the engagement and release of the clutch devices, and a cover plate detachably connected to the platen head and confining said clutch devices in place on the platen head and when removed allowing a withdrawal of any or all of the clutch devices and the spindle, said cover plate having a hub formed thereon through which the spindle passes and which is seated in a bearing in the platen frame to support one end of the platen in place.

15. The combination of a rotative platen; a line spacing wheel; clutch mechanism for connecting the line spacing wheel and platen to turn together, said clutch mechanism comprising a split ring having en-

larged ends which are of greater radial dimensions than the body of the ring and form broad contact faces at the ends of the ring, and controlling levers which are fulcrumed at their ends and each of which contacts intermediate its fulcrum and point where power is applied with the broad contact face formed by an enlarged end of the split ring, thereby separating the load point and fulcrum of each lever.

16. In a typewriting machine, the combination of a platen, a line space wheel, a split ring, a pair of levers arranged within said ring and bearing at their outer ends against the terminals of said ring, fulcras arranged 75 between the outer ends of said levers, a spring pressed spindle having a head that is provided with a transverse bore, two contacting balls arranged in said bore and each protruding to one side thereof and arranged to bear and roll on the inner ends of said levers.

17. In a typewriting machine, the combination of a platen, a platen head provided with a lug or fulcrum block, a split ring, a 90 pair of levers arranged crosswise of the ring, each lever at its outer end being arranged between one end of the split ring and one side of the fulcrum block, each lever at its inner end terminating substantially at the 95 middle of the ring but to one side of the center thereof, and each lever having a cam that extends longitudinally of the axis of the ring and also of the platen, and a spring pressed stem arranged axially of the platen 100 and provided with rollers for riding on said cam portions.

18. In a typewriting machine, the combination of a platen, a platen head provided with a lug or fulcrum block, a split ring, a 105 pair of levers arranged crosswise of the ring, each lever at its outer end being arranged between one end of the split ring and one side of the fulcrum block, each lever at its inner end terminating substantially at the 110 middle of the ring but to one side of the center thereof, and each lever having a cam that extends longitudinally of the axis of the ring and also of the platen, and a spring-pressed stem arranged axially of the platen 115 and of the ring and provided at its inner end with a transverse bore which contains two balls contacting within the bore and protruding beyond the bore and arranged to roll along the cam portions of the levers when 120 the stem is moved longitudinally.

19. In a typewriting machine, the combination with a platen, a platen head provided with a fulcrum block, a line space wheel, a split ring, a pair of levers each arranged 125 at its outer end between a terminal of said ring and one side of said fulcrum block, said levers extending inwardly transversely of the platen and having at their inner ends cam portions which extend longitudinally of 130

the platen, and a spring pressed spindle provided with means for acting on said cam portions and causing said levers to fulcrum on said block and to expand said ring into frictional engagement with said line space wheel.

20. In a typewriting machine and in a platen clutch mechanism, the combination with the line space wheel, of a divided ring, 10 two transverse levers each bearing at its outer end against a terminal of said ring, fulcra arranged between said levers, a spring pressed spindle having a transverse bore containing two contacting balls, both of 15 which protrude beyond said bore and bear and roll on the inner portions of said levers.

21. In a typewriting machine and in a platen clutch mechanism, the combination with the line space wheel, of a divided ring, 20 two loose plate-like levers arranged transversely of the ring and each having a portion which extends longitudinally of the axis of the ring and of the platen, a platen head

having independent fulcra for said levers, said fulcra being arranged within the divided portion of the ring, and means arranged axially of the platen for spreading said levers at their inner ends and causing them to act as levers of the second order upon the terminal portions of said ring. 25

22. In a typewriting machine, the combination of a platen, a line space wheel, clutching means therebetween, a pair of levers arranged transversely of the platen, independent fulcra for said levers, and a spring 30 pressed spindle having a transverse bore containing two contacting balls, both of which protrude beyond said bore and bear and roll on the inner portions of said levers. 35

Signed at Syracuse, in the county of 40
Onondaga and State of New York, this 21
day of April, A. D. 1919.
